United States Patent

Des. 240,657
Patented July 20, 1976

240,657

COMBINED RADIO, CASSETTE RECORDER AND SPEAKERS

Yutaka Sugawara, Kanagawa, Japan, assignor to
Superscope, Inc., Chatsworth, Calif.

Filed May 22, 1974, Ser. No. 472,433

Term of patent 14 years

Int. Cl. D14—01, 03

U.S. Cl. D56—4 B

Fig. 3

*Fig. 4**Fig. 5**Fig. 6*FIG. 1 is a front, top and right side perspective view of a combined radio, cassette recorder and speakers showing my new design;

FIG. 2 is a left side elevational view;

FIG. 3 is a rear elevational view;

FIG. 4 is a bottom plan view;

FIG. 5 is a front top and left side perspective view with the speakers in unhinged, separated position; and

FIG. 6 is a perspective view with the speakers in folded position.

I claim:

The ornamental design for a combined radio, cassette recorder and speakers, substantially as shown and described.
